CANE MILL ROLL

James A. H. Wodehouse, Hawi, Territory
of Hawaii

Application May 23, 1933, Serial No. 672,496

1 Claim. (Cl. 100—47)

The invention relates to cane mill rolls and has for its object to provide one or more of the rolls of a mill with a surface of a character to collect and retain bodies of bagasse or comminuted fiber, constituting a multiplicity of rough gripping areas, spots or surfaces to engage the cane and prevent slipping of the rolls, thereby insuring a substantially constant and uniform feed and increasing the efficiency of the mill, which desirable objects are attained by providing the contact surface of the roll with a multiplicity of relatively small circular holes into which the fibrous material is compacted to form rough surfaced plugs and patches and affording a gripping contact between the roll and the cane.

In the accompanying drawing

Fig. 1 is a conventional end elevation of a three roll mill in which the invention is applied to the top roll.

Fig. 2 is a side elevation of the improved roll.

Fig. 3 is a similar fragmentary view showing a modified disposition of the holes.

Fig. 4 is a fragmentary longitudinal section illustrating the application of the invention to a roll having a circumferentially ribbed and grooved surface.

Fig. 5 is a section on line 5—5 of Fig. 4.

One of the major problems of a sugar mill engineer is to attain and maintain a substantially constant and uniform feed of the cane through the crushing rolls of the mill units in order to obtain a maximum extraction of the juice from the cane, without interruption. It is necessary in order to secure a high extraction to have the mill rolls set as close to each other as is practicable. If they are set too close or if the grain of the metal of which they are made is not sufficiently open, or if the cane being milled is of the hard milling type, the rolls have a tendency to slip and refuse to feed. This causes a loss in capacity, a lowering of the extraction and a rapid wearing of the rolls, so that they take on a polish which only adds to the difficulties.

A number of devices and expedients have been suggested and tried with varying degrees of success, looking toward a constant and uniform feed of the cane through the mill rolls. Among the expedients heretofore employed are the circumferential and longitudinal grooving of the surface of one or more of the rolls, the provision of irregular holes or pittings in the surfaces of the circumferential ribs and the providing of the surface of the roll with a plurality of polygon-shaped indentations, each including a plurality of square corner steps. The principal purpose of

these structures is to increase the bite on the cane, but they are all open to the objection that they decrease the effective crushing surface of the roll and the general efficiency of the mill. The present invention is designed to effect a substantially uniform and constant feed without impairing the normal efficiency of the mill by providing the peripheral surface of at least one of the rolls of the mill with a multiplicity of relatively small holes of comparatively shallow depth and preferably disposed in parallel longitudinal rows, with the holes in successive rows arranged in staggered relation. Such an arrangement is illustrated in Figs. 1 and 2 of the drawing, in which 1 indicates the top roll of a typical mill, 15 2 the feed roll, and 3 the discharge or bagasse roll. As shown, the top roll 1 has its peripheral surface provided with multiple rows of circular holes 5, which may be formed in any satisfactory manner as by drilling, or in the operation of 20 casting the rolls. As indicated, the longitudinal rows of holes 5 extend along the surface 4 at an angle to the longitudinal axis of the roll and the holes in each row are disposed in staggered relation with reference to those in the adjacent rows, 25 so that the entire contact surface of the roll is reticulated, the individual holes preferably being of three-quarters of an inch diameter and of equal depth and a circumferential pitch of approximately three inches. 30

With this particular disposition of the holes, the latter become quickly filled with a compacted and matted mass of comminuted cane fiber or bagasse, the exposed surface of the individual plug-like masses affording a highly effective gripping contact between the roll and the cane. 35

While the invention has been illustrated as applied to but one of the rolls of a mill, it is obvious that any number of rolls may be similarly equipped. 40

While the invention has been illustrated as applied to otherwise smooth surfaced rolls, it will be understood that it is equally applicable to the conventional types of circumferentially ribbed and grooved rolls, as illustrated in Figs. 4 45 and 5, in which 6 and 7 indicate the circumferential ribs and intervening grooves, which are usually V-shape in cross section, and 5 indicates one of the multiplicity of holes or counterbores penetrating the surface of the roll to a somewhat greater depth than that of the grooves 7. In this case, the bagasse fiber is compacted into the individual holes under great pressure and the outer surface of each plug-like mass of bagasse becomes an effective gripping portion of the roll 50 55

surface to insure a uniform feed of cane without, in any way, impairing the function of the circumferential grooves and ribs, which latter may be disposed on the surface of the roll in any conventional manner, that illustrated in the drawing being the commonest form in which the individual grooves 7 are formed between adjacent walls of successive ribs 6.

As stated, the effect of the invention is to improve and enhance the feeding function of any of the standard types of cane mill rolls and it may be applied to any of the rolls of mills already installed or as component features of new installations.

What I claim is:

A cane mill roll having its periphery formed with alternating ribs and grooves extending circumferentially thereof and with openings intersecting the ribs and grooves extending below the grooves into the body of the roll, each of said openings having enclosing side walls forming a pocket permitting masses of bagasse received therein to be retained in compacted plug-like form. 5
